UNITED STATES PATENT OFFICE.

WILLIAM SMALLEY DANIELS, OF DETROIT, MICHIGAN.

DESIGN FOR A SHOCK-ABSORBER.

48,310.

Specification for Design. Patented Dec. 21, 1915.

Application filed March 26, 1915. Serial No. 17,276. Term of patent 3½ years.

To all whom it may concern:

Be it known that I, WILLIAM SMALLEY DANIELS, a citizen of the United States, residing at Detroit, in the county of Wayne and State of Michigan, have invented a new, original, and ornamental Design for a Shock-Absorber, of which the following is a specification, reference being had to the accompanying drawing, forming a part thereof.

Figure 1 is a perspective view of a shock absorber showing my new design; and Fig. 2 is a bottom plan view thereof.

I claim:

The ornamental design for a shock absorber as shown.

WILLIAM SMALLEY DANIELS.

Witnesses:

LOUISE A. JORDAN,
CLYDE L. ROGERS.
